UNITED STATES PATENT OFFICE.

JESSE PARSONS, OF SEATTLE, WASHINGTON, ASSIGNOR TO PARSONS APPLIANCE COMPANY, OF SEATTLE, WASHINGTON.

WINDOW-OPERATING MEANS.

1,421,547.

Specification of Letters Patent. Patented July 4, 1922.

Application filed June 9, 1919, Serial No. 302,655. Renewed November 1, 1920. Serial No. 421,156.

To all whom it may concern:

Be it known that I, JESSE PARSONS, a citizen of the United States, and resident of the city of Seattle, county of King, State 5 of Washington, have invented certain new and useful Improvements in Window-Operating Means, of which the following is a specification.

My invention relates to windows and the 10 manner of securing, guiding and controlling the sashes in their movements of opening and closing, and the means employed for locking said sashes in adjusted position.

The object of my invention is to provide 15 a means for mounting window sashes in window frames so as to secure certain novel and desirable results, and to better secure results which have been before secured by other means.

20 One feature of my invention is the employment of means for better holding and guiding the sash in the window frame, in which a guide strip is carried by the sash, and the frame is provided with a channel in 25 which said strip travels, and means whereby said strip may be retracted into the stile of the sash when it is desired, and thus facilitate the removal of the sash from the window frame.

30 Another feature of my invention is the employment of means whereby the window sash is supported and raised by the action of a spring and mechanism whereby the sash may be locked in adjusted position and re- 35 leased at will.

A further object of my invention is to 40 provide a guide member which enters the groove or channel in the window frame and about which the sash may turn as a pivot, so that when the guiding strip is retracted within the channel of the sash, said sash may be turned down so as to expose the outer surface of the glass for convenient cleaning by a person within the room.

45 Other objects of my invention may be determined by an inspection and study of the claims herein.

In the accompanying drawings I have shown my invention embodied in the forms 50 of construction which I now prefer to use.

Figure 1 is a side view of a window having my improved type of construction incorporated therein, portions of both the window frame and the window sashes being 55 shown broken away and in section in order

to better illustrate the construction and operation of parts.

Figure 2 is a section taken upon the line 2-2 and 2-20 of Figure 1. The section of the lower sash is taken upon the line 60 2-20, while that of the upper sash is taken upon the line 2-2.

Figure 3 is a vertical section taken approximately upon the center line of the sash and the window frame.

Figure 4 is a horizontal section taken upon the line 4-4 of Figure 1.

Figure 5 is a view of the inner or back face of the window frame at the point where the sash raising and locking means are installed.

Figure 6 is a vertical transverse section taken through a window casing showing the sash lowered and swung inward for cleaning.

Figure 7 shows, in perspective, one edge 75 of a window sash having my device mounted thereon.

Figure 8 is a perspective of the lower corner fragment of a sash showing the relative position of the rack bar when retracted into the channel in the sash.

In carrying out my invention I provide a metallic frame or casing which is designed 85 to be secured to the outer edges of the stiles of the sash, which casing has incorporated therein the guiding strip, and means for projecting and retracting the same.

The window casing employed in connection with my invention has a flush outer surface in which is formed two vertical grooves 90 for the reception of the guide strips of respectively the upper and lower sash. In other words, instead of forming guide channels by securing stops or parting strips to 95 the face of the window frame, the sash is provided with guide strips which project from the face thereof and which enter channels recessed in the face of the window casing. In Figure 2 the relative position of 100 these parts is shown.

The window frame 1 is provided with channels or grooves, 10, into which project the strips 2 which are supported by the window sash. The sashes 3 are provided on the 105 outer edges of their stiles with grooves 30, and a metallic casing 4 is secured upon each vertical edge of the sash.

This condition of the parts is shown in Figure 8 and also in Figure 3. This facing 110

or metallic casing 4 has outer wings 41 which fit closely against the side faces of the stile 3. It may be secured thereto at intervals, as by means of screws 42, so that by adjustment 5 in or out when installing the window, the over-all width of the window sash may be adjusted to fit the slight variations which are apt to occur in the separation of the sides of the window casing. Thereafter the casing 4 10 is preferably permanently secured upon the stile.

It is well-known that wood has by far its greatest expansion or contraction across the grain, rather than lengthwise, hence the fit 15 of the sash in its frame is controlled almost entirely by the expansion or contraction of its stiles. When the metal casing is permanently secured, by means of the screws 42 or other securing means placed adjacent the 20 inner edge of the stile, expansion or contraction of the wooden stile 3 within the metal casing 4 will not affect the overall width of the window sash. The screws 42 or other securing means being placed as near 25 the inner edge of the stile as is practicable, the position of the outer guiding surface of the metal casing 4 is little affected by variations in the width of the stile.

The bar 2 is provided with teeth 20, thus 30 making of it a rack bar. Means are provided whereby this rack bar may be retracted into the channel 40, or projected so as to enter the channel 10 in the window frame, in which latter position it acts as a guide for the window sash to secure proper movement thereof and to prevent removal of the sash. Various means may be provided for shifting this bar 35 so as to project and retract it. The means which I prefer to use and which have herein 40 been illustrated are as follows.

The bar 5 extends lengthwise of and bears against the inner edge of the bar 2. These two bars are held in engagement so that there 45 may be a limited longitudinal movement between the two, as by means of clips 21 carried by the bar 2, which clips extend about the bar 5. The bar 5 is connected with the controlling means by having a crank arm 60 which is secured to a short shaft 6, and 50 which is connected with the bar 5, as by means of an arm 50.

The shaft 6 preferably projects from the inner face of the sash and is provided with a button 61 or other means by which it may be 55 readily turned. It is evident that by turning this button and its attached parts, the bar 5 and the rack bar 2 which is secured thereto may be forced outward or withdrawn as desired. When withdrawn to the position 60 shown in Figures 3 and 8 the rack bar 2 no longer forms a retaining means for the window sash and the sash may be removed from the window frame, excepting as it may be held by other means.

65 At one end of the sash, preferably the

lower end, is mounted a guide block 7. This block fits the channel 10 in the window frame and is so constructed that the window sash may pivot about the same. As herein shown the block 7 is pivotally supported upon a 70 pin 70 carried by the sash. With the rack bar 2 drawn into the groove in the sash, the window sash may then be swung downward upon the pin 70 as a pivot, into the position shown in Figure 6, thereby making the inner 75 surface of the window glass accessible from within the room for cleaning. If it be desired to remove the window sash entirely from the casing, this may then be done by lifting one end of the sash until the block 7 80 is clear from the channel 10.

It is desirable that the rack bar 2 may be securely held in its projected position so that there is no tendency to accidentally recede into the channel in the sash. To secure this 85 I have provided the bar 5, upon which the bar 2 is carried, with short legs 51, which, when the bar is in retracted position, enter holes 43 in the inner part of the channel 40. These legs are of such length that when the 90 rack bars 2 are projected, as is shown in Figure 1, they engage with the outer face of the bottom web of the channel 40 and thus prevent any forcing of the bar inward.

Each stile of the sash is provided with the 95 mechanism which has just been described. At each side of the window frame and sash means are provided for raising and locking the sash. Such means employ a gear wheel, as 8, which is journaled in position 100 100 such that when the bar 2 is projected, it will mesh with the teeth of this gear.

In connection with the gear 8 is provided a spring which acts upon this gear in such manner as to tend to raise the sash. The 105 strength of the spring should be so proportioned that it will be able to lift the sash to its uppermost position. The springs 71 employed are of the kind which is used for clock springs, being flat, spirally wound strips. 110 Secured to the shaft of each of these springs are a ratchet wheel 81 and a gear wheel 80. The latter wheel meshes with the wheel 8. The object of mounting the spring upon an axis removed from that of the wheel 8, is to 115 get the same farther away from the window sash so as to permit the using of a spring of ample size.

It is evident that if this spring is of proper strength it will be able to raise the window 120 sash whenever it is released so as to permit such movement. Normally a locking dog prevents such action. In connection with the lower sash a single locking dog will be sufficient. This dog will act to prevent raising of the window sash, but would not prevent lowering thereof. Such a dog 82 is shown in Figure 1. In order to release this, a lever, as 83, is pivotally mounted on the inner face of the window frame with one end 125 130

in position to engage the dog 82 so as to release it. To the other end of the lever is secured a plunger 84, which extends to the outer face of the frame and is adapted to be engaged by, and, by pressing inward thereon, to release the dog 82.

In connection with the upper sash two locking dogs are provided, whereby the sash may be held in adjusted position against movement either up or down. This requires the use of two ratchet wheels 81 and the companion dogs 82. The releasing mechanism, however, need not be duplicated. The ends of the dogs 82 are brought together in position to be engaged at the same time by the single releasing lever 83.

By reason of the fact that the rack mechanisms above described are contained within a casing 4, which is secured upon the outer edges of the stiles of the sash, it is possible to fit these a little farther out or in when installing the window, thus securing a tight fit of the window sash in the window frame, when otherwise there would be a loose fit. Because of the manner in which the casing 4 is supported and of its nullifying the effect of expansion and contraction of the stiles 3, the teeth of the gear 8, which are quite small, will always mesh with the teeth of the rack bar 2. Without provision of some such means the casing 4 would have to be adjusted in or out continually to keep these teeth in mesh, for otherwise shrinkage of the stile 3 would withdraw the rack bar from mesh.

The strip 2 which forms the rack bar should be made of metal and the facing 4 for the edges of the sash should also be made of metal. This being so, it is possible to obtain a snug fit which will prevent wind from blowing through without securing any binding action. These parts being also made of metal are not liable to warp, as would be the case were they made of wood.

The roller 25 which is journaled in the upper end of the guide bar 2 is designed to bear upon the bottom of the groove in the window frame when the bar 2 is projected. This prevents the possibility of this end of the bar scraping and wearing the bottom of the groove by reason of the sash moving up and down.

A window sash equipped with this sort of apparatus may be opened as much as desired and automatically locked in this position. If a sash be equipped with the double locking mechanism such as has been described as applied to the upper sash, this sash could not be moved up or down, without releasing the same by the action of one of the buttons 84. If, however, this is not desired, a single locking means in connection with a spring 71 which is not sufficiently powerful to raise the window, may be employed. This will serve to prevent opening of the sash further

than is desired and will permit closing without releasing the locking mechanisms, as has been described in connection with the lower sash. Whether a single or double locking mechanism is employed is immaterial. 70

I do not deem it necessary to provide the locking mechanism described except at one side of the window. At the other side of the window the window sash supporting and releasing mechanism may be left free to act 75 at all times. It is, however, desirable to provide means for locking the spring against running down whenever the rack bar is retracted into the channel in the sash. Such a device is shown at the left hand side of the 80 Figure 1. The locking dog 9 is adapted to engage a ratchet wheel, as 81, which wheel operates in the same manner as the gear wheel of the mechanism previously described. This dog, however, has on one end 85 a roller 90 which engages with the outer face of the rack bar. These parts are so adjusted that when the rack bar is in its outermost position the engagement thereof with the roller 90 releases the locking dog 9 and 90 when the rack bar is retracted, the roller 90 carried by the dog 9, swings outward and thus engages the locking end of the dog with the ratchet wheel 81. Therefore, the act of retracting the rack bars 2 serves to automatically apply the lock to the sash raising mechanism at this side of the window. 95

What I claim as my invention is:

1. The combination with a window sash of a permanently projecting guide block pivoted at one end of the sash and adapted to enter the sash retaining groove of the window frame and to permit swinging of the sash thereon as upon a pivot, and a guide strip alined therewith at the same side of the 100 sash and adapted to be projected and withdrawn at will, to enter and withdraw it from the sash retaining groove of the window frame.

2. The combination of a window sash having a channel extending lengthwise of a stile, a guide strip adapted to be entirely received in said channel, means for projecting or retracting said guide strip at will, a window frame having a guiding channel adapted to 105 receive said guide strip, and a guide block pivoted upon one end of the stile and entering said guiding channel in the frame. 110

3. The combination of a window sash having a channel extending lengthwise of a 120 stile, a guide strip adapted to be entirely received in said channel, means for projecting or retracting said guide strip at will, a window frame having a guiding channel adapted to receive said guide strip, and a 125 guide block pivotally secured upon one end of the stile and entering said guiding channel in the frame, said guide block being permanently projected and non-retractile.

4. The combination with a window sash 130

having a stile channeled in its outer edge, of a guide strip adapted to be entirely received in said channel, the ends of said channel being closed, a strip secured to the inner edge 5 of the first mentioned strip to permit a relative longitudinal movement therebetween, a crank arm journaled upon the stile and pivotally connected with the inner of said strips, inwardly projecting legs carried by 10 said inner strip and adapted to engage the bottom of the channel when the strips are projected, the stile having supplemental recesses into which said legs enter when the crank arm is swung to retract the said strips 15 within the channel.

5. In combination, a window sash and a frame therefor, a rack bar carried by a stile of said sash and engageable with said frame, means for retracting said rack bar 20 from said frame and for projecting it towards the same, sash-raising means secured in said frame and engageable with said rack bar when the latter is projected, and means 25 operable by retraction of said rack bar for locking said sash-raising means in fixed position.

6. In combination, a window sash and a frame therefor, said sash having a channel extending lengthwise of a stile, and said 30 frame having a sash-retaining channel parallel and registering with said channel in the sash, a rack bar carried by said sash, means for retracting said rack bar into said channel in the sash stile and for projecting it 35 into the sash-retaining channel, sash-raising means secured in said window frame and engageable with said rack bar when the rack

bar is retracted for locking said sash-raising means in fixed position.

7. In combination, a window-sash and a frame therefor, said sash having a channel extending lengthwise of a stile, and said frame having a sash-retaining channel parallel and registering with said channel in the sash, a rack bar carried by said sash, 40 means for retracting said rack bar into said channel in the sash stile and for projecting it into the sash-retaining channel, a pinion secured in said frame and engageable with said rack bar when the latter is projected, a 45 ratchet wheel rotatable by said pinion, a spring operable to rotate said ratchet wheel, and a dog engageable with said ratchet wheel, and having an end tending to be projected into said sash-retaining channel thereby to lock said ratchet wheel against rotation, and engageable by said rack bar when the latter is projected thereby to release said ratchet wheel. 50

8. In combination with a window sash 60 having stiles and with a window frame, means for automatically nullifying transverse expansion or contraction in each of said stiles comprising metal casings each fixed to the inner edge of its respective stile 65 and extending thereover, and cooperating with said window frame to form guides for the sash, and cooperating sash-raising members, a part thereof being secured in the window frame, and others in said metal cas- 70 ing.

Signed at Seattle, Washington, this 4th day of June, 1919.

JESSE PARSONS.
